UNITED STATES PATENT OFFICE.

EDGAR G. PORTER, OF WOODLAWN, PENNSYLVANIA.

CATCHER FOR COATING-MACHINES.

1,316,644.

Specification of Letters Patent. Patented Sept. 23, 1919.

Application filed March 4, 1919. Serial No. 280,517.

To all whom it may concern:

Be it known that I, EDGAR G. PORTER, residing at Woodlawn, in the county of Beaver and State of Pennsylvania, a citizen 5 of the United States, have invented or discovered certain new and useful Improvements in Catchers for Coating-Machines, of which improvements the following is a specification.

10 My invention relates to apparatus for catching and conveying sheet material, the faces of which are coated or otherwise so treated that they are easily scratched or marred. While unlimited in apparatus for 15 catching any particular kind of sheet material, my invention is particularly applicable to what is known as a catcher mounted upon the top of a tin-pot in a tin plate manufacturing plant. The purpose of such pot 20 is to receive the tinned plates as they pass from the tin pot and to cause them to advance to a conveyer or other apparatus.

As usually constructed such catchers include a pair of parallel rotatable shafts, 25 upon which there are keyed, or otherwise rigidly secured, metal disks arranged in pairs. One of the shafts is mounted in bearings backed by springs so that the faces of all the disks of one shaft are as a unit 30 held yieldingly toward the faces of the disks of the other shaft.

In the use of catchers such as just briefly described it has been found that when two or more plates simultaneously pass edge-to-edge between the disks, the lateral separation between one pair of disks may, by reason of the thickness of one plate, be so great as to prevent other disks from contacting with the faces of a thinner plate. 35 Also, it has been found that by increasing the spring pressure upon the yieldingly mounted shaft in an attempt to cause all disks to engage the plates fed between them, some of the plates (usually the thicker 40 ones) are scratched or otherwise marred by excessive pressure.

The object of my invention is to provide a catcher wherein the disks of each pair are capable of receding the one from the other 45 independently of any movement of relative recession of the disks of another pair or of the shafts upon which the disks are mounted, whereby any desired number of plates of different thicknesses may simultaneously 50 pass edge-to-edge between the disks carried

upon two parallel shafts without liability of scratching or otherwise injuring any of the plates.

In the accompanying drawings which form part of this specification I have illustrated the preferred embodiment of my invention. Figure 1 shows the machine in vertical longitudinal central section of the machine; Fig. 2 a view in vertical transverse section on the plane indicated 60 by the line II—II in Fig. 1; Fig. 3 a plan view, and on somewhat larger scale, of the arrangement of rolls in the frame; Fig. 4 an end elevation of the frame shown in Fig. 65 3; Figs. 5 and 6 transverse sections of the frame, the planes of section being indicated by the lines V—V and VI—VI, Fig. 3; and Fig. 7 a view in longitudinal section through 70 one of the sleeves on one of the shafts shown in Fig. 3, the plane of section being indicated at VII—VII, Fig. 3.

In the illustrated embodiment of my invention the tin pot, which may be of any suitable construction, is incompletely illustrated at 1. In the upper part of the tin-pot there is arranged a pair of delivery rolls 2 adapted to be driven in any suitable manner, and above such rolls and upon the tin-pot the catcher is mounted. The catcher includes a supporting frame 3 hung to a pivot-post 4 and capable of being swung laterally on such pivot-post to and from the operative position above the tin-pot in which it is shown in the drawings. This frame when brought to operative position is braced by 80 the extensible legs 5. In this frame, and directly above the delivery rolls 2, extend shafts 6, geared to rotate in unison and in opposite directions, one of them being positively driven from a suitable source of 85 power, preferably the same source as used for driving the rolls 2, as shown in Fig. 1. These two shafts so geared together are yieldingly supported, so that they are capable of approaching one another under spring 90 pressure or receding from one another by 95 spring tension. For such purpose, as indicated particularly in Figs. 3 and 4, both shafts are journaled on boxes 15 which are so mounted in the frame as to float between 100 oppositely acting springs 16, 17 and 18, the 105 tension of which may be adjusted as by set screws 19.

The shafts 6 are provided each with a succession of disks 7, preferably made of 110

metal, which rotate in unison with the shafts themselves. These disks are so arranged that they coöperate two-by-two, a disk on each of the two shafts forming one of each 5 pair of disks, and between these pairs of disks the material is caught and moved upwardly. To the end that the disks of each pair may recede one from the other independently of the movements of the disks 10 of the other pairs or of the movement of the shafts, the disks 7 are preferably mounted, not directly on the shafts 6, but on sleeves 8, and such sleeves in turn are mounted on shafts 3. These sleeves surround the shafts, 15 and rotate in unison with the shafts, but there is a looseness of fit between shaft and sleeve, which allows a limited amount of lateral play of sleeve on shaft. While this may be accomplished in various ways, Fig. 20 7 shows the shaft to be provided externally with a collar 9 and the sleeve to be provided internally with a bushing 10, the collar and bushing being interlocked by tongue and groove engagement. The construction is such that while there is a limited 25 lateral play of sleeve on shaft, the two parts rotate in unison.

As seen particularly in Fig. 3, the sleeves 30 8 are externally engaged, preferably each at two points near the opposite ends, by 35 saddles 11. These saddles 11 are carried upon arms extending from frame 3, and are spring-backed, the tension of the backing springs being adjustable by nuts 25 on the bolts 12. The construction is such that each 40 of these sleeves, while it is rotatable with each of the shafts which it surrounds, is also yieldingly held at the range of its lateral movement and is extended as far as possible 45 toward the companion shaft. As already stated, the disks 7 are carried, not on the shaft, but on the sleeves, and it is preferable to mount upon each sleeve two disks, one at each end adjacent to a saddle 11. The disks then coöperate two-by-two in single floating pairs. As is indicated in Fig. 3, the shafts may be indefinitely extended in length,

and the number of disks may be indefinitely increased.

In the operation of the catcher two or 50 more sheets of different gages may be simultaneously engaged by the catcher, and the pressure of each pair of disks, being independently applied, will be such as to properly grip the plates without marring them. 55

I claim as my invention:

1. In a catcher for plate-coating machines, the combination of a frame, rotary disks borne by said frame in two series, the disks of one series coöperating with those of the other series, the two series of disks being yieldingly held each as an entirety in operative relative positions, and the several disks being movable against spring pressure independently of other disks in the same 6 series.

2. In a catcher for plate-coating machines, the combination of a pair of rotary shafts arranged parallel one to another, and yieldingly held adjacent one to another, a plurality of disks borne by each of said shafts, the disks borne by one shaft being movable with respect thereto against spring pressure in a direction transversely of the shaft, maintaining in the range of such movement 7 a unity of rotation with the shaft.

3. In a catcher for plate coating machines, the combination of a pair of rotatable shafts arranged in parallel position and spring-im- 3 pelled each toward the other, a plurality of 4 sleeves surrounding each of said shafts, each connected to its shaft and rotatable therewith, the said sleeves being spring-imelled laterally upon the sustaining shaft in a direction toward the opposite shaft, and disks 8 borne integrally upon said sleeves at opposite ends thereof.

In testimony whereof I have hereunto set my hand,

EDGAR G. PORTER.
